UNITED STATES PATENT OFFICE.

GEORGE L. HARVEY, DECEASED, LATE OF CHICAGO, ILLINOIS; BY HELEN A. HARVEY
AND KELLOGG FAIRBANK, EXECUTORS, OF CHICAGO, ILLINOIS.

BOLSTER CUSHION.

Application filed May 17, 1924. Serial No. 714,034.

To all whom it may concern:

Be it known that GEORGE L. HARVEY, deceased, formerly a citizen of the United States, and resident of Chicago, in the 5 county of Cook and State of Illinois, did invent certain new and useful Improvements in Bolster Cushions, of which the following is a specification.

The invention relates to springs or cushion- 10 ions for bolsters of car trucks and particularly to an improvement on the construction shown in the prior patent to George L. Harvey, No. 1,454,509, of May 8, 1923.

The improvement contemplates the adap- 15 tation of the shock-absorbing elements of the draft-rigging of said prior patent to a spring support for car bolsters.

One of the particular advantages in the 20 use of the peculiarly shaped spring elements is the absence of any objectionable rebound. The reason for this is that much of the force is absorbed by friction. This renders the elements particularly useful for bolster 25 cushions.

25 A design is disclosed herein in which the spring plates which constitute the cushion elements are confined in proper assembled 30 relation between two castings, a tie member preventing separation but permitting 35 compression to the required extent. This provides a cushion unit which may be easily handled, shipped and installed in the usual position without skill on the part of the workmen or possibility of error in the manner 40 of installation.

The invention will be more readily understood by reference to the accompanying drawings, wherein,

45 Fig. 1 is an end view of a cushion unit consisting of pairs of plates and upper and lower confining members therefor;

Fig. 2 is a side view thereof;

Fig. 3 is a top plan view;

Fig. 4 is a sectional view on the line 45-45 of Fig. 1;

Fig. 5 is a sectional view on the line 5-5 of Fig. 2; and,

Fig. 6 is a plan view of one of the friction plates.

50 As before stated, the improvement is intended to utilize the friction plates disclosed in the prior Harvey patent above referred to. These plates are of angular form in end elevation, the side portions 10,

11 being joined at the angle by a portion 12. 55 These plates are constructed in pairs, the plates composing a cooperative pair being oppositely laterally deflected so that normally only the edges of the plates are in contact. This is best illustrated in Fig. 4. 60 When a force is applied tending to move one plate or a pair toward the other, frictional resistance is encountered and the resistance increases as the area in contact increases due to the approach of the wings 65 to a parallel relation.

In constructing the device of this invention a plurality of pairs of plates constructed as described are associated and confined in proper relation between upper and 70 lower castings 13, 14. The lower casting is of skeleton construction and comprises angularly inclined walls 15, 16, supported at their sides by walls 17, 18, and at their 75 ends by walls 19, 20. The lower margins of these walls are in a plane and the lower surface is shaped to cooperate with the ordinary spring-seat of a car-truck side frame. The walls 15, 16, constitute a 80 tapered projection the angle of which corresponds to the angle of a plate resting thereon.

The upper casting includes walls 21, 22, angularly disposed and constituting a recess 85 shaped to correspond to the angular shape of the upper surface of a spring plate. In order that the plates may be suitably confined against possible lateral movement, the side wings or aprons 23, 24, are provided 90 which are integral with the top wall 25 of the casting. The wings are stiffened by triangular webs 25^a which project diagonally downward from the top wall, and occupy spaces in the notches in the spring plates. Dowels 25^b project upwardly from the top wall and may engage similarly shaped recesses in a bolster A, shown in dotted lines in Figs. 1 and 2, and in full lines in Fig. 4.

100 As a means for confining the plates in a unit adapting the device for handling and installation as such, the vertical bolts or rivets 26 are provided, the heads of which are mounted within the space beneath the angular projection of the lower casting while the opposite ends are passed through the top wall 25 of the top casting. Preferably the parts are riveted after being 105

assembled and the springs are preferably slightly initially compressed. The position of the heads of the rivets relative to the base of the casting is such that freedom of vertical movement is permitted to the extent of the full compression of the spring plates. This is possible because the space at the center of the angular projection is utilized as a chamber for the reciprocation of the bolts. As will be understood, the shanks of the bolts pass through the plates at a point of the end notches 27 therein.

A spring cushion constructed as described may be assembled complete in the factory and handled, shipped and installed without difficulty or possible error. Changes in the form shown may be made without departure from the spirit of my invention.

The claims are:

20 1. In a device of the class described, the combination of a pair of opposed members each having surfaces disposed at an obtuse angle, the surfaces being convex on one member and concave on the other member, 25 angular spring plates between said members, said plates being notched at the angle, one of said members having depending side wings, and inside webs for bracing said

wings, said webs being accommodated in the notches in the plates.

2. A device for providing spring support for bolsters comprising in combination a supporting member of skeleton construction providing plane surfaces disposed at an obtuse angle in convex relation, a vertically arranged mating member of skeleton construction having oppositely disposed plane surfaces in concave relation, said last named member having depending side portions, webs connecting the side portions to the main portions of said members, and spring plates held between said upper and lower members, said plates having portions adapted to cooperate with said concave and convex surfaces, the plates having side notches adapted to receive the web of the mating member.

Signed at Chicago, county of Cook and State of Illinois, this 9th day of May, 1924.
